(57) **CLAIM**

The ornamental design for a twist-tie for closing packages, as shown and described.

DESCRIPTION

FIG. 1 is a perspective view of a fully unbent phase of our new design for a twist-tie for closing packages; and, FIG. 2 is a front elevation view thereof.

The broken lines depict portions of the twist-tie for closing packages that form no part of the claimed design.

1 Claim, 2 Drawing Sheets

FIG. 1

FIG. 2
